UNITED STATES PATENT OFFICE

HATTIE R. SPECHT, OF NORFOLK, VIRGINIA

MACHINE FOR PERFORATING TRANSFER SLIPS

Application filed May 5, 1930. Serial No. 448,920.

This invention relates to improvements in a machine for perforating transfer slips. It is intended that this machine be of small size so that it may be readily carried in the hands or mounted wherever convenient for hand operation. The machine is adapted for accurately and rapidly perforating or punching transfer slips of the kind which are issued by conductors or other operators of street cars, busses and the like. Transfers of the kind used are customarily provided with markings indicative of each of the conditions under which they may be used, for example, the names of the route from which they are issued; the direction of travel and the time limit allowed. Where such transfer slips are issued individually by the operator there is therefore necessitated a separate punching for each of the conditions to be indicated. This frequently results in delay and error when the operator is called upon to issue a transfer slip in haste.

It is an object of my invention to provide a machine which may be set to perforate the transfers as they are successively issued. It is also a purpose to provide for the perforation of certain designations independently of the attention of the operator. These designations which are intended to independently may include the issuing route; and the appropriate time limit which applies to all slips to be issued at that time.

A further object of my invention is to make possible the accurate perforation of the slip to show such designations as may be called for in individual cases, for example, the route and direction for which the transfer is to be issued.

It will be apparent from the following description that the machine is adapted for carrying out other related objects within the range of the disclosures. As the preferred form of my invention I have illustrated the same in the accompanying drawings in which;

Fig. 1 is a side elevation of the perforating machine;

Fig. 2 is a plan view thereof;

Fig. 3 is a vertical longitudinal section on the line 3—3 of Fig. 2; 50

Fig. 4 is a transverse vertical section on the line 4—4 of Fig. 1;

Fig. 5 is a transverse vertical section on the line 5—5 in Fig. 1;

Fig. 6 is a transverse vertical section on the line 6—6 of Fig. 1; 55

Fig. 7 is a transverse vertical section on the line 7—7 of Fig. 1;

Fig. 8 is a transverse vertical section on a reduced scale on the line 8—8 of Fig. 1; and 60

Fig. 9 is a view of the transfer slip.

As shown in the drawings the machine consists of a box or frame 11 preferably of die-cast or machined metal. The left hand portion of the box contains the supply of 65 blank transfer slips which are fed through the perforating mechanism mounted within the right hand portion of the box. The box has a top 12 bolted or otherwise fastened over it and forming a cover for the perforating mechanism and also a punch plate for use in conjunction with this mechanism. At the inner end of the top there are two up-standing lugs 13, 13 which form journals for a transverse pivot and bearing pin 14. 70 The pin 14 extends beyond the lugs 13, 13 to form pivots for a second cover while the portion between the lugs 13, 13 forms a journal. 75

A loose roller 15 is journalled on the pin 80 14 between the lugs 13, 13. This roller 15 has a friction surface for engaging the transfer slip as the latter will successively feed from the supply to a position beneath the punch plate 12.

The second cover plate 16 extends over the slip holding and feeding mechanism. It has an opening 16a through which the feeding operation may be observed and the supply of slips watched so that the same may be re- 90

plenished when exhausted. Offset lugs 17, 17 formed at the inner end of the plate 16 are pivoted on the ends of pin 14 so that the cover plate is thus hinged over the box. The outer end of the cover plate 16 has a raised portion 18 forming a housing to receive a feed roller. The extreme end of the cover plate extends downwardly to form a flange having a catch 20 by which the cover is held against the end of the box by means of a spring detent 21 mounted on the latter.

Beneath the punch plate 12 the box carries a punch holding plate 22. Lugs 23 on the inner surface of the latter form journals for a transverse pivot pin 24 which in turn carries a tray 25. The tray extends from the lugs 23, 23 substantially to the opposite wall of the box and serves to hold a block of blank transfer slips. These slips are held in position by means of a vertical flange 26 around the sides and free end of tray 25. Beneath the free end of tray 25 is a pair of bosses 27 extending downwardly and opposite to a similar pair of bosses 28 extending upwardly from the base of the box. An expansion spring 29 is fitted on each pair of opposing bosses 27, 28 so as to force the tray 25 and the block of transfer slips upwardly into contact with the feeding mechanism.

The housing 18 of the cover plate 16 carries a shaft 30 having an attached roller 31 with a friction surface extending slightly below the lower surfaces of the cover plate 16. A gear wheel 32 is mounted at one end of shaft 30 as shown in Fig. 4.

Between the sides of the casing and beneath the shaft 30 there is mounted a transverse shaft 33 which carries a gear wheel 34 engaging wheel 32.

Referring to Fig. 3 it will be evident that gear wheel 34 has six spaced openings 35 which serve to permit a step by step rotation for the shaft 33. A spring detent 36 is attached to the side of the casing at 37 and has a laterally projecting lug 38 fitting the hole 35 in the gear wheel 34 and limiting the rotation of the latter. Means to cause the rotation of gear wheel 34 consists of a drum 39 mounted on shaft 33 with a spring motor. The latter may be wound in any suitable manner such as by a sleeve 40 surrounding the end of shaft 33 and adapted for rotation by a key or crank.

The lug 38 which is normally held in one of the holes 35 may be released from the hole and thus permit the wheel 34 to commence rotation by means of the following release mechanism. This consists of a pedestal 41 extending upwardly from the base and opposite the lug 38. This pedestal forms a slide bearing for a pin 42 having slightly less diameter than the lug 38. One end of the pin slides into the hole 35 in gear wheel 34 while the opposite free end of the pin 42 is received in a recess 43 on a rock arm 44. The rock arm 44 forms

part of a rock shaft 45 which is carried on the base of the box by means of journal 46, 46. The pin 42 is normally held out of the plane of the gear wheel 34 by means of a helical spring in the pedestal 41.

In operation the rock shaft 45 forces the pin 42 into contact with lug 38 causing the latter to be withdrawn from the hole 35 in the gear wheel 34. The spring motor operating on the latter causes it to pass in front of the lug 38 so that retraction of the pin 42 permits the gear wheel 34 to rotate until the pin 38 engages in the next hole 35. During this action the roller 31 has rotated in contact with the uppermost transfer slip in the tray and caused it to slide far enough to be engaged by the feed roller 15 and its associated parts.

The feed roller 15 is effective by reason of the following feeding mechanism. A shaft 47 is journaled transversely of the casing and beneath the friction roller 15. This shaft 47 has a pair of oppositely disposed rollers 48, 48 each of which has a friction surface. The mid-portion of the shaft 47 carries a coil spring 49 the end of which is attached to the pin 24 between the pivot members of the tray 25. The spring 49 may be wound up by rotating the shaft 47 by means of a key or crank in a manner well understood while the shaft and its rollers is prevented from rotation in the feeding direction by suitable locking means.

This consists of a recess 50 in the periphery of one of the rollers 48. A lug 51 is mounted on the base of the box beneath roller 48 and carries a bar 52 pivoted for vertical movement. The free end of the bar has an upwardly standing latch 53 which may be forced into the recess 50 in locking engagement. The free end of the bar is beveled to provide a tooth 54 by which the bar may be depressed to release the latch 53 from engagement with the roller. The spring 55 is seated within a recess in the base and bears upwardly against the bar to insure engagement of the latch 53 in recess 50 except when the bar 52 is depressed.

Referring to Fig. 5 it will be observed that the shaft 54 carries an enlargement 56 in which is a dog 57 mounted on pivot 58. This dog 57 is held outwardly by a spring and when the rock shaft 45 rotates counter-clockwise the dog 57 engages tooth 54 to depress the bar 52 and release the latch 53 from the roller 48. This permits the roller to rotate in a clockwise direction as shown in Fig. 3. As soon as the dog 57 has passed beyond the plane of the tooth 54, the latter springs upward to catch and hold the roller 48 at the end of its complete revolution. When the shaft 45 rocks back to its original position the dog 57 rides over the tooth 54 without moving the bar 52.

Operation of the feeding mechanism so far

described is caused by a rocking motion of the shaft 45. This permits the rollers 48 to make a single revolution. One end of the uppermost transfer slip has already been engaged between rollers 48 and roller 15 by the previous feeding movement carried out by roller 31. As the rollers 48 move the transfer slip is fed to the right as shown in Fig. 3 and into position above the punching mechanism. As this transfer slip is advanced, the next succeeding one from the block is engaged at the rear edge by the roller 31. Since the rocking of the shaft 45 has released the gear wheel 34 from the lug 38, the latter makes a partial revolution which causes the roller 31 to operate. On retraction of the shaft 45 the pin 42 withdraws from gear wheel 34 and permits the latter to rotate until the lug 38 follows into the next succeeding hole 35.

The amount of rotation permitted to gear wheels 32 and 34 serves to advance the transfer slips far enough for the front edge of the slip to be seized between the rollers 48 and 15 which have completed their delivery of the preceding slip to the punching mechanism. The second transfer slip is therefore in a position to be advanced into the punching mechanism on the next rocking movement of the shaft 45. It will thus be apparent that the operation of the feeding of one blank slip into the position of punching is followed by the advance of the second blank into position to be similarly fed forward.

In Fig. 9 there has been shown a typical transfer slip for which this device is intended. This slip usually provides in suitable spaced arrangement printed indications first of the particular route on which the transfer is to be used; second the direction of travel and third the time of day. At least two perforations must be made in the group of directions in order to indicate from which point and to which point the travel is authorized; one perforation is required to indicate the route itself and one designation to indicate the time of issue. Generally speaking this device provides a separate group of manually adjusted punches for the route and this requires no change by the operator. A similar group of manually adjusted punches indicate the direction of travel by the setting of one of the punches of this group and this requires no further adjustment as long as the travel is continued in this direction. A further manual adjustment of the third group of punches indicates to which route the transfer is authorized. This latter adjustment of the punch is operated in conjunction with the act of punching the slip. In addition to the above the appropriate time limit to be punched is set by means of clock work which operates periodically and without attention from the operator. The following punch setting or adjusting mechanism

is provided. Referring particularly to the designation of the route or line of travel issuing the transfer, the punches 59 are provided in number equal to the entries on the printed form. These punches are carried in vertical passageways in the punch holder 22. The passageways register with openings 60 in the top or die-plate 12 of the casing. The lower portions of the passageways are enlarged as shown at 61 to form bearings for the enlarged portions 62 of the punches 59. Coil springs 63 are placed around the punches 59 in front of the enlargement 62 and operate to retract the punches. Beneath the punches there is a platform 64 supported above a pair of parallel links 65, 65 which connect the platform 64 pivotally to bosses 66, 66 on the base. The platform 64 is caused to rise and fall by means of a rocker 67 mounted upon rock shaft 45 and connected by means of links 65, 65 to the links 65, 65.

The side walls of the casing have openings 68 opposite the plungers 59. Pull-levers 69, 69 pass through the opening 68 and terminate beneath the punches 59 in cam surfaces 70, 70.

One pull lever 69 of this group is drawn out from either side of the casing at the option of the operator and serves to raise the appropriate punch 59 the height of the wedge surface on the pull lever. It follows that the punch so affected will be brought into advanced position so that as the platform 64 rises under the rocking of the shaft 45, the punch 59 will rise into the opening 60 of the die-plate 12. In making this movement the punch will perforate the printed transfer slip at the appropriate place as the slip is held in the depressed channel 71.

Separate groups of punches are provided for perforating the transfer slip to indicate the points from which and to which transfer is issued. The punches 72 which serve to indicate the points from which travel is authorized are mounted to reciprocate in member 22 in the manner above described and have their lower ends resting upon the pull levers 73 with the wedge faces 74 of the latter in position to adjust the punches vertically when the latter is drawn out from the casing. The pull levers are shown in Fig. 8 to rest on a platform 75 which in turn is supported on the links 76 above the bosses 77 in the base. The openings 78 in the side wall of the casing are sufficiently wide to permit the rise of the levers 73 when the platform 75 is raised by rocking the shaft 45 in the manner already described. It follows that the appropriate punch 72 will perforate the desired designation.

A separate group of punches 79 is provided to indicate the direction to which travel is authorized. These punches are carried in member 22 and have their rear ends resting upon cams 79a mounted on links 80

pivoted to the base. These links 80 are individually connected by links to rocking sleeves 81 loosely journaled on rock shaft 45. The sleeves 81 have extensions 82 passing through openings 83 in the base of the casing. Operating plungers 84 are journaled in housings 85 beneath the base of the casing.

The plungers 84 have extensions 86 pivoted at 87 to the members 82 and coil spring 88 serve to hold the plungers in an extended position.

It follows that when the selected one of the group of plungers 84 is pushed inward overcoming spring 88, the punch 79 will be raised through the transfer slip and into the opening 60 of the die-plate 12.

A series of collars 89 is fastened to the rock shaft 45 between the sleeves 81. Ratchets 90 on collars 89 and corresponding spring-held teeth 91 on sleeves 81 serve to rock the shaft 45 whenever one of the rocking sleeves 81 rotates.

This sets in motion the punching operations previously described and also the forward feeding of the slips and the delivery of the punched slip as soon as the punches are retracted.

In order to punch the time limit on the slip there is provided a series of punches 92 mounted within the member 22 in the manner already described. These punches are set in four rows of twelve each and each row has beneath it a cam roller 93 on which there are four cams 94, 95, 96, 97 spaced in successive 90 degree angular relation. Each cam roller 93 is extended into a housing 98 at one side of the casing and there terminates in a gear 99. The four gears 99 are in line and mesh each with the other. One of said cam shafts 93 is projected to carry a pair of grooved gears 100, 101 and through the covering 102 the shaft may be operated by the setting wheel 103.

Beneath the gear wheels 100, 101 are a pair of levers 104, 105 respectively. These levers terminate opposite star wheels 106 and 107 respectively, both mounted on a shaft 108 transversely held beneath the casing as at 109 and adapted to receive timing clockwork.

The upper ends of the levers 104, 105 are pivoted at 110 and carry teeth 111 which engage the grooves in wheels 100, 101. In this manner wheel 99 is caused to rotate by a step by step movement and successively bring a cam 94 into position beneath a punch 92. The shafts 93 are carried on a platform 112 which in turn is supported on the links 113. The upper ends of links 113 have cam faces 114. The links are connected by cross links 115 and 116 to a rocking arm 117 on shaft 45. It follows that as the rock shaft is operated the punch 92 will be caused to perforate the time in the manner already described.

The above description indicates the several instrumentalities used and the manner

of co-operation. With the tray 25 carrying a block of separate transfer slips the operator sets one of the punches 59, one of the groups of punches 69 while the clock work train will set one of the punches 92 to register the time limit. Through the actuation of one of the plungers 84 the remaining group of punches 78 has one of the latter directly actuated. At the same time the rocking movement of rock shaft 45 causes the punches 59, 69 and 92 to perforate the slip. As soon as the plunger 84 is released the punches are retracted and the slip is fed out of the channel 71. In the meantime the feeding mechanisms have been released and a second slip is fed into the groove 71 by roller 15 while a third slip is advanced by roller 31. The operation may then be repeated either with the punches already in advanced position or by such others in adjustment as the circumstances make desirable.

The above description of my preferred form is given for purpose of illustration without limiting the invention other than by the scope of the following claims.

What I claim is:

1. In a device of the class described, a plurality of groups of punches, cam-operating members for selectively advancing a punch from each group into operative position, means for giving each group of punches an operative stroke, a common actuating element for said last named means, a separate group of punches and periodically operating means for positioning one of these punches for an operative stroke, said means being operatively connected to said common actuating element.

2. In a device of the class described, a plurality of groups of punches, manual means for selectively advancing a punch from each group into operative position, a separate group of punches, time-controlled means for selectively advancing one of said punches, means for giving each group of punches an operative stroke, a common actuating element for said last named means, a group of punches having individual operating plungers and connections between said plungers and the common actuating element.

3. In a device of the class described, a group of line identifying punches, a group of direction punches, manual means for selectively advancing a punch from each group into operative position, a group of time punches, time-controlled means for selectively advancing one of said punches, means for giving each group of punches an operative stroke, a common actuating element for said last named means, a group of destination punches having individual operating plungers and connections between said plungers and the common actuating element.

4. In a device of the class described, means for separating a paper slip from a supply

thereof, means for feeding the slip to position to be punched, a plurality of groups of punches, means for selectively advancing a punch from each group into operative position, a common actuating means for the punches and for the separating and feeding of the slip and an independent group of punches having individual operating plungers operatively connected with the common actuating means.

10 In testimony whereof I affix my signature.
H. R. SPECHT.
